(57) CLAIM

The ornamental design for a block plane chamfer guide, as shown and described.

DESCRIPTION

FIG. 1 is a perspective view showing the top, one end and the stationary side of the block plane chamfer guide design of this invention.

FIG. 2 is a top view of the guide of this invention shown in FIG. 1.

FIG. 3 is an end view of the guide of this invention shown in FIG. 1, of which the opposite end is a mirror image.

FIG. 4 is a side view of the stationary side of the guide of this invention shown in FIG. 1.

FIG. 5 is a side view of the movable side of the guide of this invention shown in FIG. 1; and,

FIG. 6 is a bottom view of the guide of this invention shown in FIG. 1.
